UNITED STATES PATENT OFFICE.

EMIL R. DRAVER, OF RICHMOND, INDIANA.

WHEEL CARRIER.

1,418,134.

Specification of Letters Patent. Patented May 30, 1922.

Application filed December 31, 1917. Serial No. 209,763.

To all whom it may concern:

Be it known that I, EMIL R. DRAVER, a citizen of the United States, residing at Richmond, in the county of Wayne and State 5 of Indiana, have invented certain new and useful Improvements in Wheel Carriers; and I do hereby declare the following to be a full, clear, and exact description of the invention, such as will enable others skilled 10 in the art to which it appertains to make and use the same.

My present invention has for its object to provide an improved carrier and enclosing receptacle for extra wheels and demountable 15 rims of automobiles and is in the nature of a modification of, or improvement on the so-called "tire carrier" disclosed and claimed in my earlier application, Serial Number 157,971, filed of date, March 28, 1917. Generally 20 stated, the invention consists of the novel construction and combination of parts hereinafter described and defined in the claims.

In my above noted prior application, tire 25 carriers of this general type are broadly disclosed and broadly claimed, but, as specifically disclosed, the back plate of the combined carrier and enclosing receptacle was independent of the body structure proper, 30 was spaced from the back thereof, and, together with a supplemental spindle or clamping bolt, was secured to or supported from a cross bar or bracket at the rear of the machine.

In accordance with the present invention, 35 the back or inner plate of the combined carrier or receptacle is incorporated with, or made a part of the back structure of the automobile body and is directly supported 40 therefrom, so that part of the back of the body constitutes a part of the main receptacle.

This improved arrangement not only gives 45 compactness in construction, but eliminates the necessity for more or less expensive intermediate connections between the running gear and carrying receptacle, and at the same time, gives a very intimate and rigid connection between the tire and receptacle. 50 This may be brought about in a good many different ways, all, however, involving the same general or broad feature of construction, in that a portion of the body constitutes a portion of the carrying receptacle 55 and the latter is directly connected to and supported from the said body. Moreover,

with this improved arrangement, a rigidly supported spindle for carrying an extra wheel and for clamping the outer plate against the inner or back plate and against 60 the tire of the demountable wheel or rim, is not required since any kind of an axially disposed clamping bolt will insure this purpose.

The invention, in its several slightly varying forms is illustrated in the accompanying drawings wherein like characters indicate like parts throughout the several views.

Referring to the drawings;

Fig. 1 is a rear elevation with some parts 70 broken away, showing what is believed to be the preferred form of the carrier applied to or incorporated with the body of an automobile;

Fig. 2 is a view chiefly in side elevation 75 but with some parts in vertical section and some parts removed, of the parts shown in Fig. 1;

Fig. 3 is a detail in section on the line 3—3 of Fig. 1, some parts being removed; 80

Fig. 4 is a right side elevation of the parts shown in Figs. 1 and 2;

Fig. 4^a is a view corresponding to Fig. 4, 85 illustrating a slightly modified form and with some parts in vertical section;

Fig. 5 is a fragmentary view in vertical section on the line 5—5 of Fig. 1, showing in cross section the demountable rim and tire within the carrying receptacle;

Fig. 6 is a detail in section on the same 90 line as Fig. 5 but showing only the upper portion of the inner or back plate of the carrying receptacle;

Fig. 7 is a view corresponding to Fig. 1 but illustrating a slightly modified construction; 95

Fig. 8 is a side elevation of the parts shown in Fig. 1, some parts being broken away and some parts being shown in vertical section; 100

Fig. 9 is a view corresponding to Fig. 1, but illustrating a further modified construction of the carrying receptacle; and

Fig. 10 is a side elevation of the parts shown in Fig. 9, some parts being removed 105 and some parts being broken away.

In all of the views wherein the following parts are shown, the numeral 11 indicates the rear wheels, the numeral 12 the frame side bars, the numeral 13 the rear springs 110 and the numeral 14 the gasoline tank, and 15 the body shell of the automobile, which

latter as is well known, is customarily made of sheet metal over a suitable framework 15^a.

Referring first to the construction illustrated in Figs. 1, 2, 3, 4, 5 and 6, the numeral 16 indicates the pressed metal back plate of the carrying receptacle, the same, as shown, being formed independent of the body shell 15 and being diametrically divided on a horizontal line, and at its intermediate edges 10 having riveted thereto marginal metal angle strips 17 which, by means of a plurality of small nut-equipped bolts 18, are rigidly clamped together. This back or inner plate 16 noted is dish-shaped, so that it is adapted 15 to receive the main portion of a tire and demountable rim or extra wheel. The back of the body shell 15 is cut out to receive the upper portion of this dished back plate 16 and adjacent to that part of the said back 20 plate 16 that is interposed in the opening formed in the back of said body shell, the latter is formed with an out-turned flange 19 that is riveted to the adjacent or contacting portion of the said back plate 16. Thus a 25 very direct and rigid connection is made between the body shell 15 and the upper portion of the back or inner plate of the carrying receptacle, so that the upper portion of the latter becomes, in effect, a part of the 30 automobile body proper. The lower portion of the back plate 16, it will be noted, projects below the bottom of the automobile body, and for this reason, it is made detachable so that for the purposes of completing 35 and assembling the automobile, the lower portion of the said plate 16 may be removed to permit the vehicle body to be set upon the floor without damage to the permanently attached part of the carrying receptacle.

40 The outer or cover plate 20 of the carrying receptacle is preferably a sheet metal rim pressed into concavo-convex form and having a reinforced margin that is adapted to fit quite closely over the projecting rim of the back plate 16. To securely clamp the outer or cover plate 20 onto the rim of the back plate, I provide an axial clamping bolt 21, which, in the preferred arrangement best shown in Fig. 3, has its headed end seated in a flanged hub 22 which, by means of a rivet 23, is shown as permanently secured to the lower angle strip 17 of the lower portion of the back plate 16 and is rigidly but detachably secured to the angle strip of the permanent or fixed upper portion of said back plate by a short nut-equipped bolt 24. This construction permits the spindle to be removed with the lower portion of the said plate 16.

60 The projecting end of the bolt 21 is threaded and the outer or cover plate 20 is provided with an axial perforation that adapts it to be slipped onto the projecting end of said bolt. By means of a nut 25 that works with 65 threaded engagement on the projecting end

of the bolt 21, the plate 20 may be firmly clamped onto the back plate 16. Preferably and as shown, the nut 25 is provided with a projecting arm or hand piece 26, by means of which it may be easily rotated to tighten or 70 loosen the same.

When an extra wheel is applied in the carrying receptacle, the clamping bolt 21 will pass through the hub thereof but without contact therewith, so that the wheel will 75 be carried through the tire by the plates of such receptacle. The tire-equipped demountable rim will be carried in the same manner. Preferably, the two plates of the carrying receptacle are so formed that they 80 will closely engage the enclosed tire and hold the extra rim or wheel rigid, and thereby prevent it from vibrating or jumping about within the receptacle.

The tire-equipped wheel or demountable 85 rim must, of course, be placed in the dished back plate 16 while the outer or cover plate 20 is removed; and to prevent the same from toppling out of this back plate, while the hands are removed therefrom to apply the 90 cover plate, I provide a hook-like retaining spring or flange 27 shown in Figs. 5 and 6. In applying the wheel or rim, the top of the tire is first put into the hook 27 and then the bottom of the tire is pressed into the lower 95 portion of the back plate 16. The rim or wheel will then be held while the cover plate is being applied.

The construction illustrated in Fig. 4^a differs from the construction just above described, in that the body sheet 15 is pressed inward at 15^b, so as to afford a pocket to receive the upper portion of the dished back plate 16. Also, in this modification, the back plate 16 is secured to inwardly pressed portion 15^b by short nut-equipped bolts or rivets, only one of which is indicated at 28.

The construction illustrated in Figs. 7 and 8 is like that illustrated in Figs. 1 to 6, inclusive, except that the back plate 110 16^a is made in a single piece.

The construction illustrated in Figs. 9 and 10 differs from the constructions illustrated in the other views in that the back of the body 15 is not cut or mutilated and in that 115 the back plate 29 of the carrying receptacle, at its upper half portion, has a rearwardly projected marginal flange that is made to fit the outline of the back of the shell 15, and terminates in an out-turned lip that is 120 rigidly connected to said shell 15 by rivets 30. In this construction, also, the clamping bolt 21^a, which is otherwise like the clamping bolt 21, is made longer and is secured to a hub 22^a secured to the lower back portion of the shell 15 in line with the axis 125 of the carrying receptacle.

It is thought from the foregoing description to be obvious that the several effects and objects set forth in the introductory 130

part of this description are obtained in all of the several illustrated forms of the carrying receptacle. Moreover, a carrying receptacle designed on the plan indicated is 5 not only strong and durable and compact, but gives quite an attractive appearance to the automobile.

In the drawings, Figs. 1, 2, 4 and 4^a, about one-half of the tire carrier projects 10 below the bottom of the body of the vehicle, but the extent of this projection can, of course, be varied. For vehicles having tops that can be lowered, the carrier will be set much lower than for enclosed cars.

15 The described arrangement of the tire carrier would make it possible to locate the gasoline tank at the rear rather than in front; as shown in the drawings.

What I claim is:

20 1. The combination with an automobile body, of a carrying receptacle for extra wheels or rims, comprising a back plate incorporated as a rigid part of said body, the lower portion thereof being projected below said body, a cover plate detachably applied to said back plate with its lower portion also projecting below the bottom of said automobile body, and a cover securing device applied to the central portions of said 25 back plate and cover, that portion of said back plate that is below said securing device being detachable from said body.

25 2. The combination with an automobile body, of a carrying receptacle for extra 30 wheels or rims comprising a concave back plate, and a cover, the upper portion of said back plate being set into the back of said body and incorporated as a permanent part thereof, and the lower portion of said back 35 plate being projected below the bottom of said body, said back plate and cover being engageable at their rims, and a spindle

rigidly secured to the central portion of said back plate and through said back plate directly to said body approximately at the 45 lower portion of the latter, said spindle being extended centrally through said cover and having a clamping device at its outer end, that portion of said back plate that is below said spindle being detachable from 50 said body.

3. In a tire and wheel carrier structure, the combination with a vehicle body, of a cylindrical casing and cover therefor, said body having a recess formed in the rear 55 thereof adapted to receive said casing, and means for securing said casing within said recess.

4. In a tire and wheel carrier construction, the combination with a vehicle body 60 having a recess formed in the rear thereof, a cylindrical casing secured in said recess and adapted to receive a tire, or wheel and tire, and a circular cover for said casing telescoping over the same at its outer edge 65 and adapted to contact with the tire, or the tire and wheel in the casing to hold the same firmly in position, and means for securing said cover in place.

5. The combination with a vehicle body 70 having a recess formed in the rear thereof, of a tire and wheel carrier structure comprising a cylindrical casing adapted to be received in and secured in said recess, a circular disk cover for said casing, and 75 means disposed centrally of said casing and disk for holding the latter in position.

In testimony whereof I affix my signature in presence of two witnesses.

EMIL R. DRAVER.
